LA RUE B. CHEVALIER, OF IOLA, KANSAS.

PULVERIZED-COAL-FEEDING APPARATUS.

1,203,703.

Specification of Letters Patent.

Patented Nov. 7, 1916.

Application filed March 6, 1916. Serial No. 82,898.

To all whom it may concern:

Be it known that I, LA RUE B. CHEVALIER, a citizen of the United States, residing at Iola, in the county of Allen and State of Kansas, have invented certain new and useful Improvements in Pulverized-Coal-Feeding Apparatus, of which the following is a specification.

The object of my invention is to provide a novel, simple and efficient apparatus for feeding powdered or pulverized coal and air to a burner or burners for fuel purposes, said apparatus having provision: firstly, whereby the fuel may be delivered from a common source of supply to a number of burners in a single furnace or to a number of burners of two or more separate furnaces, dispensing with the use of a separate coal bin and feeding device for supplying each burner; secondly, whereby it becomes possible, with the use of powdered coal as fuel, to maintain furnaces of larger area than heretofore at a substantially even temperature throughout; thirdly, whereby a predetermined pressure of air carrying the proper quantity of powdered coal for fuel may be maintained in a passageway which is connected to and feeds a number of separate burners; fourthly, whereby the air may be caused to circulate through an endless passageway, so that any coal carried by the circulating air which passes all the burners without being fed to them may be again returned to the burners; fifthly, whereby any desired number of the plurality of burners connected to the main fuel supply passageway may be open for operation at any time; sixthly, whereby the main fuel supply passageway may be supplied with powdered coal from a suitable bin during the operation of the apparatus; seventhly, whereby the unused coal passing the burners may be returned to the supply bin; eighthly, whereby the air pressure in the main fuel supply passageway may be automatically regulated by the pressure itself; ninthly, whereby the separator or dust collector usually employed in pulverized coal feeding apparatus, may be dispensed with; and, finally, whereby various novel advantages are gained.

With this object in view my improved apparatus consists of the elements and the combinations of them hereinafter fully described and claimed.

In the accompanying drawings illustrat-

ing my invention: Figure 1 is a top view of a portion of a furnace and my improved pulverized coal feeding apparatus. Fig. 2 is an elevation thereof. Fig. 3 is a vertical section, on line 3—3 of Fig. 2. Fig. 4 is a detail in section, showing the means for automatically regulating the air pressure within the fuel supply pipe.

Referring to the drawings, 2 designates a closed bin adapted to contain the pulverized coal to be fed to the burners and having a portion of its top wall raised to form a horizontally extending channel 4, as shown. Adjacent to the bin 2 is a fan or blower 5; and connected to the outlet of the fan 5 is one end of the main fuel supply pipe 6. The other end of the pipe 6 communicates with the upper portion of the bin 2 and discharges downwardly into one end portion of the channel 4 therein. Leading upwardly from the other end portion of the channel 4 is a pipe 7 which extends to the fan 5 and is connected to the inlet thereof. The pipes 6 and 7 and the walls of the bin 2 and the casing of the fan 5 form an endless passageway through which air may be caused to circulate, in the direction of the arrows in Fig. 2, by the operation of the fan 5. The operating shaft 8 of the fan 5 is provided with a pulley 9 by means of which the fan 5 may be actuated at any desired speed by any suitable power.

The powdered coal is fed from the bin 2 into the pipe 7 or circulating passageway by the mechanism which I shall now describe. The lower portion of the bin 2 is made tapering, and opens into one end of a cylinder or pipe 10. The other end of the pipe 10 is connected to the pipe 7 by a short vertical pipe 11, as shown, the pipes 10 and 11 forming a passageway which connects the bin 2 and pipe 7. Extending centrally through the pipe or cylinder 10 is a shaft 12 carrying a screw conveyer 13, by means of which the powdered coal is advanced from the bottom of the bin 2 through the pipe 10 and discharged through the pipe 11 into the pipe 7. The shaft 12 is journaled in the end walls of the cylinder or pipe 10; and one end of the shaft 12 extends outwardly and is provided with a pulley 14, which may be driven by any suitable power at any desired speed to actuate the conveyer 13, the speed of which determines the quantity of coal fed to the pipe 7.

The pipe 6 extends adjacent to a furnace

15; and projecting from the pipe 6 are rows of discharge pipes or burners 16 which enter openings 17 in the wall of the furnace 15 and discharge into the furnace. Each pipe or burner 16 is controlled by a suitable valve 18 which may be opened and closed as desired, so that any desired number of the burners 16 may be open or in operation at the same time. When the conveyer 13 is actuated to feed the powdered coal from the bin 2 to the pipe 7, and the fan 5 is driven to circulate the air through the pipes 6 and 7, air and powdered coal are driven through the pipe 6 to the burners 16 by the operation 10 of the fan 5, the air pressure in the pipe 6 being determined by the speed of the fan 5; and the air and coal are discharged from the open burners 16 and into the furnace 15 to feed the fire therein. The coal carried 15 by the air within the pipe 6 in excess of that fed to the open burners 16 is returned through the pipe 6 to the bin 2 which acts as a collector as the current of air circulating through the pipes 6 and 7 passes through 20 the bin 2.

As the air and coal are discharged from the burners 16 it becomes necessary to admit additional air to the circulating passageway back of the fan 5, and for this purpose I provide the following: The pipe 7 is provided 25 with a valve 19 comprising a cylindrical casing 20 and a valve head 21 slidable within the casing. The lower portion of the casing 20 opens into the pipe 7 and the upper portion 30 of the casing 20 has slots or openings 22 therein adapted to admit outside air to the casing 20 and pipe 7 when the valve body 21 is raised above the bottom of the openings 22. The valve head 21 is connected by a 35 link 23 to an arm 24 which is pivoted at 25 on a suitable support 26; and the arm 24 is connected by a link 27 to one arm 28 of a lever 29 which is fulcrumed, at 30, on a suitable support 31. The other arm 32 of the 40 lever 29 is provided with a set of separable and removable weights 33 and is connected by a link 34 to the upper end of a piston 35 which is slidable in a cylinder 36. The cylinder 36 is secured on the pipe 6 and opens 45 into the same exposing the lower end of the piston 35 to the pressure within the circulating pipe 6. The arm 32 of the lever 29 carrying the weights 33, is held up against 50 a stop 37 by the air pressure within the pipe 6 acting against the bottom of the piston 35; and, in this position of the parts, the valve 19 is closed. Now, when the air pressure within the fuel supply pipe 6 falls below 55 a predetermined point, controlled by the weights 33 and the speed of the fan 5, the piston 35 permits the weights 33 to lower the arm 32 of the lever 29, thereby raising the arm 28 of the lever 29 and raising the 60 arm 24 and valve head 21 to admit air to the pipe 7 through the openings 22 until 65

the pressure produced by the fan 5 within the pipe 6 is raised to the said predetermined point; whereupon the said pressure acts against the piston 35 and raises the weighted arm of the lever 29 and closes the 70 valve 19. It will thus be seen that the pressure within the supply pipe 6 is automatically maintained at a given point by the pressure itself. It will also be seen that the point at which the pressure is automatically 75 maintained may be varied by changing the weights 33 and by changing the speed of the fan 5, or both.

The powdered coal is fed to the bin 2 through a vertical pipe 38, the lower end of 80 which discharges into the bin 2 away from the channel 4 therein and below the open end of the circulating pipe 7 leading from the bin, to prevent the coal entering the bin 2 through the pipe 38 from being carried from 85 the bin by the air passing out through the pipe 7. The upper end of the feed pipe 38 communicates with a horizontal pipe or cylinder 39 having a feed screw or conveyer 40 therein which is operative to feed coal 90 through the pipe 39 to the pipe 38, and which, with the coal being fed thereby, serves as a seal to prevent air from entering the bin 2 through the feed pipe 38, during 95 the operation of the apparatus.

I claim:

1. In a pulverized coal feeder, the combination of a closed coal bin, pipes connected to said bin and forming therewith a closed, endless circulating passageway, means to circulate air through said passageway, means to supply one of said pipes with coal from said bin without permitting air to pass from the bin with the coal, and a discharge pipe leading from one of said pipes. 100

2. In a pulverized coal feeder, the combination of a coal bin, a closed circulating pipe communicating with said bin and adapted to receive coal therefrom, means to circulate air through said pipe, and a discharge pipe leading from the circulating pipe. 110

3. In a pulverized coal feeder, the combination of a coal bin, a closed circulating pipe, means operative to supply said pipe with coal from said bin, means to circulate air through said pipe, and a discharge pipe leading from the circulating pipe. 115

4. In a pulverized coal feeder, the combination of a closed coal bin, a circulating pipe discharging into and leading from the upper portion of said bin, means to discharge pulverized coal from the lower portion of said bin and into said pipe, means to circulate air through said pipe, and a discharge pipe leading from the circulating pipe. 120

5. In a pulverized coal feeder, the combination of a closed coal bin, a circulating pipe discharging into and leading from the 125

130

upper portion of said bin, means to supply pulverized coal to the bin, means to discharge pulverized coal from the lower portion of said bin and into said pipe, means to 5 circulate air through said pipe, and a discharge pipe leading from the circulating pipe.

6. In a pulverized coal feeder, the combination of a closed coal bin, a circulating 10 pipe discharging into and leading from the upper portion of said bin, a supply pipe communicating with the bin at a point below the point where the circulating pipe leads from the bin, means to discharge pulverized coal 15 from the lower portion of said bin and into said pipe, means to circulate air through said pipe, and a discharge pipe leading from the circulating pipe.

7. In a pulverized coal feeder, the combination of walls forming a closed, endless 20 circulating passageway, means to circulate air through said passageway, a discharge pipe leading from said passageway, and means to feed pulverized coal to said passageway, the last named means including 25 walls forming a supply passageway communicating with the circulating passageway, and a conveyer within the supply passageway and operative to advance coal there- 30 through.

8. In a pulverized coal feeder, the combination of walls forming a closed, endless 35 circulating passageway, means to circulate air through said passageway, a discharge pipe leading from said passageway, and means to feed pulverized coal to said passageway, the last named means including 40 walls forming a supply passageway communicating with the circulating passageway, and a screw conveyer within the supply passageway and operative to advance coal therethrough.

9. In a pulverized coal feeder, the combination of a closed coal bin, a circulating 45 fan, a pipe connecting the upper portion of said bin and the inlet of said fan, a pipe connecting the upper portion of said bin and the outlet of said fan, said fan being operative to circulate air through said pipes, a 50 discharge pipe leading from the second named pipe, and means to supply said pipe with coal from said bin.

10. In a pulverized coal feeder, the combination of a closed coal bin, a circulating 55 fan, a pipe connecting the upper portion of said bin and the inlet of said fan, a pipe connecting the upper portion of said bin and the outlet of said fan, said fan being operative 60 to circulate air through said pipes, walls forming a supply passageway connecting the lower portion of said bin and one of said pipes, a conveyer within said supply passageway and operative to advance coal there- 65 through, and a discharge pipe leading from the second named pipe.

11. In a pulverized coal feeder, the combination of a closed coal bin, means to supply pulverized coal to the bin, a circulating fan, a pipe connecting the upper portion of said bin and the inlet of said fan, a pipe connecting the upper portion of said bin and the outlet of said fan, said fan being operative to circulate air through said pipes, a discharge pipe leading from the second named pipe, and means to supply said pipe with 70 coal from said bin.

12. In a pulverized coal feeder, the combination of a closed coal bin, means to supply pulverized coal to the bin, a circulating fan, a pipe connecting the upper portion of said bin and the inlet of said fan, a pipe connecting the upper portion of said bin and the outlet of said fan, said fan being operative to circulate air through said pipes, walls forming a supply passageway 85 connecting the lower portion of said bin and one of said pipes, a conveyer within said supply passageway and operative to advance coal therethrough, and a discharge pipe leading from the second named pipe.

13. In a pulverized coal feeder, the combination of walls forming an endless circulating passageway, means to circulate air through said passageway, a discharge pipe leading from said passageway, means to feed pulverized coal to said passageway, and means controlled by the air pressure within said passageway to automatically supply air thereto.

14. In a pulverized coal feeder, the combination of a feed pipe, means to blow air through said pipe, means to feed pulverized coal to said pipe, and means controlled by the air pressure within said pipe to automatically regulate the air pressure therein.

15. In a pulverized coal feeder, the combination of a coal bin, a circulating pipe communicating with the bin and adapted to receive coal therefrom, means to circulate air through said pipe, a discharge pipe leading from the circulating pipe, and means controlled by the air pressure within said pipe to automatically regulate the air pressure therein.

16. In a pulverized coal feeder, the combination of a coal bin, a circulating pipe, means to supply said pipe with coal from said bin, means to circulate air through said pipe, means controlled by the air pressure within said pipe to automatically supply air thereto, and a discharge pipe leading from the circulating pipe.

17. In a pulverized coal feeder, the combination of a closed coal bin, a circulating pipe discharging into and leading from the upper portion of said bin, means to discharge pulverized coal from the lower portion of said bin and into said pipe, means to circulate air through said pipe, means controlled by the air pressure within said 125 pipe.

- pipe to automatically supply air thereto, and a discharge pipe leading from the circulating pipe.
18. In a pulverized coal feeder, the combination of a closed coal bin, a circulating pipe discharging into and leading from the upper portion of said bin, means to supply pulverized coal to the bin, means to discharge pulverized coal from the lower portion of said bin and into said pipe, means to circulate air through said pipe, means controlled by the air pressure within said pipe to automatically supply air thereto, and a discharge pipe leading from the circulating pipe.
19. In a pulverized coal feeder, the combination of walls forming an endless circulating passageway, means to circulate air through said passageway, a discharge pipe leading from said passageway, means to feed pulverized coal to said passageway, a valve adapted to be operated to admit outside air to said passageway, and means controlled by the air pressure within said passageway for opening and closing said valve.
20. In a pulverized coal feeder, the combination of walls forming an endless circulating passageway, means to circulate air through said passageway, a discharge pipe leading from said passageway, means to feed pulverized coal to said passageway, a cylinder communicating with said passageway, a piston within said cylinder and adapted to be actuated by the air pressure within the passageway, and means operated by said piston to open and close communication between said passageway and the outside air.
21. In a pulverized coal feeder, the combination of walls forming an endless circulating passageway, means to circulate air through said passageway, a discharge pipe leading from said passageway, means to feed pulverized coal to said passageway, a cylinder communicating with said passageway, a piston within said cylinder and adapted to be actuated by the air pressure within the passageway, a valve adapted to be operated to admit outside air to said passageway, and means operated by said piston to automatically supply air thereto.
22. In a pulverized coal feeder, the combination of walls forming an endless circulating passageway, means to circulate air through said passageway, a discharge pipe leading from said passageway, means to feed pulverized coal to said passageway, a cylinder communicating with said passageway, a piston within said cylinder and adapted to be actuated by the air pressure within the passageway, a weighted lever connected to and operated by said piston, a valve adapted to be operated to admit outside air to said passageway, and means operatively connecting said lever and said valve, whereby said valve will be opened and closed by said lever as the air pressure within said passageway varies.
23. In a pulverized coal feeder, the combination of walls forming an endless circulating passageway, means to circulate air through said passageway, a discharge pipe leading from said passageway, and means to feed pulverized coal to said passageway, the last named means including walls forming a supply passageway communicating with the circulating passageway, a conveyer within the supply passageway and operative to advance coal therethrough, a cylinder communicating with said passageway, a piston within said cylinder and adapted to be actuated by the air pressure within the passageway, a valve adapted to be operated to admit outside air to said passageway, and means operated by said piston for opening and closing said valve.
24. In a pulverized coal feeder, the combination of walls forming an endless circulating passageway, means to circulate air through said passageway, means to feed pulverized coal to said passageway, a plurality of valved discharge pipes leading from said passageway, and means controlled by the air pressure within said passageway to automatically supply air thereto.
- In testimony whereof I affix my signature hereto.

LA RUE B. CHEVALIER.
